CLARENCE E. SMITH, OF NAUGATUCK, CONNECTICUT, ASSIGNOR TO JOHN B. RUSS,
OF SHELTON, CONNECTICUT.

WEBBING BUCKLE.

Application filed May 15, 1928. Serial No. 277,850.

My invention relates to webbing buckles and has for its object to provide a thin webbing buckle having the end of the webbing swaged thereto. It further has for its object 5 to provide a buckle which is simple to manufacture and apply. Also a buckle in which the webbing is held by a combined swedging and clamping action.

The following is a description of an embodiment of my invention reference being had to the accompanying drawings, in which:

Figure 1 shows a front elevation of a device embodying my invention;

Fig. 2 is a side elevation of a portion of the 15 same;

Fig. 3 is a section on the line 3—3, Fig. 1;

Fig. 4 is a front elevation of the buckle proper with the clasp elevated;

Fig. 5 is a partial section on the line 5—5, 20 Fig. 4; and

Fig. 6 is a view, on a reduced scale, of the blank from which the gripping and clamping plate is formed.

Referring more particularly to the drawings, Fig. 1 illustrates a garter having the usual webbing 2 and loop member 4. 6 is the buckle comprising a wire link 8 having a clamping member 10 journaled on its upper portion, the clamping member being provided with the ordinary teeth 12. The lower end of the buckle is surrounded by a bent plate 14, having two upwardly projecting portions 16 and 18 between which the end 20 of the webbing 2 is gripped. The link may be made of 30 wire with its ends separated a considerable distance as shown, thus reducing the metal in the link. The upper portion 16 of the plate is provided with a backwardly turned flange 22 which cooperates with the upper end 24 of the rear flange 18 to clamp the webbing as it passes between them. The web is, therefore, gripped at two points i. e. between the opposing upright faces of the members 16 and 18 and between the jaws 22 and 24, forming a 40 very strong and positive securing means for the webbing. The rear reach of the webbing 2 passes downward and the webbing then is passed through the loop 14 and then upward and through the link 8 where it is engaged by 45 the clamp 10 when that clamp is in clamping position. The downward pull upon the rear reach of the webbing tends to turn the plate 14 clockwise, Fig. 3, and in order to prevent such turning I provide the front portion 16

with two lateral projections 26 which engage the front surface of the loop.

The upward projections 16 and 18 both lie substantially within the plane of the link 8 so as to not increase the thickness of the buckle. Furthermore, there is but one thickness of 60 webbing on each side of the link so that the body of the combined buckle and webbing is not as thick as where three thicknesses of webbing are present.

The buckle is a strong buckle and easy to 65 manufacture. In securing the webbing to the plate 14, the plate can be turned anti-clockwise around the lower portion of the link so as to leave the projections 16 and 18 fully exposed for the action of the press. After the 70 end of the webbing is thus secured it is passed through the link and the plate 14 turned into an upright position, whereupon the webbing is passed through the loop 4 and again through the link 8, as shown in Figs. 2 and 3. 75

As will be evident to those skilled in the art, my invention permits various modifications without departing from the spirit thereof or the scope of the appended claims.

What I claim is:

1. In a device of the character described, the combination of a link, a clamping lever journaled on the upper end thereof, and a plate surrounding the lower end thereof and having upwardly projecting portions for receiving the end of a webbing and means holding said portions in upwardly projecting position.

2. In a device of the character described, the combination of a link, a clamping lever 90 journaled on the upper end thereof, and a plate surrounding the lower end thereof and having upwardly projecting portions for receiving the end of a webbing and means holding said portions in upwardly projecting position, the front portion having a rearwardly turned flange forming with the end of the rear portion a clamp for the end of the web.

3. In a device of the character described, the combination of a link, a clamping lever 100 journaled on the upper end thereof, and a plate surrounding the lower end thereof and having upwardly projecting portions for receiving the end of a webbing and means holding said portions in upwardly projecting position, the front portion having a rearwardly turned flange forming with the end of the rear portion a clamp for the end of the web, the 105

upwardly projecting portions and clamp both gripping said webbing.

4. In a device of the character described, the combination of a link, a clamping lever journaled on the upper end thereof, and a plate surrounding the lower end thereof and having upwardly projecting portions for receiving the end of a webbing and means holding said portions in upwardly projecting position, the front portion having a rearwardly turned flange forming with the end of the rear portion a clamp for the end of the web, the upwardly projecting portions and clamp both gripping said webbing, and being substantially in the plane of said link.

5. In a device of the character described, the combination of a link, a clamping lever journaled on the upper end thereof, and a plate surrounding the lower end thereof and having upwardly projecting portions for re-

ceiving the end of a webbing and means holding said portions in upwardly projecting position, said means consisting of lugs projecting laterally from the front portion.

6. In a device of the character described, the combination of a link, a clamping lever journaled on the upper end thereof, and a plate surrounding the lower end of said link and having upwardly projecting portions for receiving the end of a webbing and means holding said portions in upwardly projecting position, and a webbing having its end secured by said clamp and extending downwardly behind said plate and then upwardly in front of said plate and through said link.

In testimony whereof, I have signed my name to this specification this 11th day of May, 1928.

CLARENCE E. SMITH.
